[57] **CLAIM**

The ornamental design for a hanger for a telephone handset, as shown.

DESCRIPTION

FIG. 1 is a front isometric view of a hanger for a telephone handset showing my new design;

FIG. 2 is a front elevation thereof;

FIG. 3 is a top plan view thereof;

FIG. 4 is a side elevation thereof;

FIG. 5 is an elevation of the side opposite FIG. 4;

FIG. 6 is a bottom plan view thereof; and

FIG. 7 is a rear elevation thereof.
